UNITED STATES PATENT OFFICE.

ROBERT J. MCKAIN, OF PHILADELPHIA, PENNSYLVANIA, ASSIGNOR TO JOHN F. SIMONS AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY, (TRADING AS SIMONS BRO. & COMPANY.)

DESIGN FOR A KNIFE-HANDLE.

SPECIFICATION forming part of Design No. 34,315, dated April 2, 1901.

Application filed February 19, 1901. Serial No. 48,011. Term of patent 7 years.

To all whom it may concern:

Be it known that I, ROBERT J. MCKAIN, of the city and county of Philadelphia, State of Pennsylvania, have invented and produced a new and original Design for a Knife-Handle, of which the following is a specification.

My design is shown in the accompanying drawing, which illustrates a knife-handle having the design applied to the surface thereof.

The design resides in the ornamentation which is applied to the surface of the handle. As shown, this consists of the representation of a clock or watch face *a*, surmounted by the head of an elk or deer *b*, with a foliate ornamentation *c c* arranged adjacent to the sur-

rounding edge or rim *d*, which terminates at the ends in fleur-de-lis *e*.

The leading or distinguishing features of the design are the elk's or deer's head and clock-face when arranged substantially as shown.

What I claim as new, and desire to secure by Letters Patent, is—

The design for a knife-handle substantially as shown and described.

In testimony of which invention I have hereunto set my hand.

ROBT. J. MCKAIN.
